UNITED STATES PATENT OFFICE.

ARTHUR E. TROIEL, OF BERKELEY, CALIFORNIA.

PROTECTIVE ARMOR.

Application filed March 23, 1927. Serial No. 177,565.

This invention relates to a metallic flexible armor and especially to an armored sole structure for shoes, boots and the like whereby puncturing of the sole and injury to the 5 foot by means of nails and sharp objects is prevented.

The present invention is especially applicable to shoes, boots, etc., as worn by mechanics in the building trades, for instance, 10 carpenters and the like and in fact farmers and other persons whose occupation is such as to expose them to the danger of jumping or stepping on sharp nails, glass, etc. For instance, carpenters, particularly when working 15 on wooden buildings are continuously jumping or climbing down from scaffolds and ladders and are continuously exposed to upturned nails while walking about and as such are continuously exposed to puncturing of the shoe soles and injury to their 20 feet. A number of attempts have been made to render shoe soles puncture-proof against nails and the like, for instance, a continuous 25 steel plate has been placed and secured in the shoe between the inner and outer sole or the sole has been made excessively hard and thick. Attempts of this character have, 30 however, proven more or less impractical as the sole loses all flexibility and the shoe becomes too stiff and heavy for comfortable wear.

The object of the present invention is to generally improve and simplify the construction and operation, particularly of armored 35 shoes, to provide an armored sole which may be permanently secured in a shoe between the inner and outer sole or placed within the shoe as an insole, to provide an armored sole which is flexible, to provide an armored 40 sole consisting of steel strips which overlap each other so as to promote flexibility and so as to provide a double thickness of metal to prevent puncture; and further to provide 45 means whereby the steel strips are held at cooperative position with relation to each other and against accidental removal. The invention is shown by way of illustration in the accompanying drawings in which:

Fig. 1 is a side elevation of a shoe showing 50 the sole thereof in section, said view also showing the armored sole interposed between the inner and outer sole,

Fig. 2 is a plan view of the armored sole showing its size with relation to the shoe 55 sole,

Fig. 3 is an enlarged section taken on line 3—3, Fig. 2,

Fig. 4 is an enlarged perspective view of a portion of the armored sole.

Referring to the drawings in detail, particularly Fig. 1, A indicates the quarters of a shoe, B the counter, C the heel, D the vamp, E the toe cap and F the sole. The sole usually consists of an insole 2 secured to the welt of the shoe and an outer sole 3. The descriptive matter so far submitted merely discloses a standard form of shoe and it is described merely for the purpose of explaining the subject matter of the present invention. The armored sole forming 60 the subject matter of the invention is best illustrated in Figs. 2, 3 and 4. It consists of a piece of fabric generally indicated at G which is cut to the shape of a sole. This fabric is provided with a series of upper and 65 lower transversely disposed pockets such as shown at 4 and 5, the pockets forming receptacles and retainers for a series of steel strips 6 extending crosswise of the fabric and the sole of the shoe. The pockets 4 and 5 70 formed in the fabric are so arranged that the steel strips will overlie each other and form a laminated structure such as shown in Figs. 3 and 4. This is of material importance as it permits comparatively thin strip steel to 75 be employed; it promotes flexibility and it furthermore presents a double layer of metal to prevent puncturing of the sole. The pockets formed in the fabric are sufficiently 80 separated as indicated at 7 to maintain a slight separation between the adjoining steel strips in each layer and to permit free movement of the steel strips with relation to each other when the sole bends, thereby further increasing flexibility. The pockets, first of 85 all, serve the function of maintaining the steel strips in superposed arrangement. They, secondly, secure the steel strips against movement with relation to the longitudinal axis of the sole and the fabric also prevents 90 endwise removal of the individual steel strips as the fabric is preferably saturated with an adhesive such as rubber cement or the like. The armored sole may be placed 95 within the shoe in the form of an insole or it may be permanently secured in the sole of a shoe by placing it between the inner 100 and outer soles as shown in Fig. 1. In either instance the foot is protected against 105 injury as stepping or jumping on a nail as 110

illustrated in Fig. 1 will only permit puncturing of the sole until contact is made with the steel strips. Further penetration is then prevented as the nail will either bend 5 or flatten on the point due to the double thickness of steel employed. The armored sole may run from the point of the shoe to the heel so as to cover the instep of the shoe or it may be extended in under the 10 heel if desired as shown in Fig. 1. The armored sole is preferably smaller than the main or outer sole as shown in Fig. 2, this being important as an ample edge or margin 15 is thereby provided for the stitching or nailing whereby the outer sole is secured to the inner sole.

While certain features of the present invention are more or less specifically described and indicated, I wish it understood that various changes may be resorted to within the 20 scope of the appended claims; similarly, that the materials and finish of the several parts employed may be such as the manufacturer may dictate or varying conditions or uses 25 may demand.

Having thus described my invention what I claim and desire to secure by Letters Patent is:—

1. A flexible protective armor consisting 30 of a plurality of superposed layers of metallic plates, said plates being laid side by side in each layer with the plates in one layer staggered with relation to the plates in an adjacent layer and means whereby the plates 35 in the respective layers are secured against displacement with relation to each other.
2. A flexible protective armor consisting 40 of a plurality of superposed layers of metallic plates, said plates being laid side by side in each layer with the plates in one layer staggered with relation to the plates in an

adjacent layer and flexible means securing the plates side by side and in staggered relation.

3. A flexible protective armor consisting 45 of a plurality of superposed layers of elongated comparatively narrow thin flexible steel strips, said strips being laid side by side in each layer with the strips in one layer staggered with relation to the strips in an 50 adjacent layer and means securing the strips side by side in each layer and in staggered relation.

4. A flexible protective armor consisting 55 of a plurality of superposed layers of elongated comparatively narrow thin flexible steel strips, said strips being laid side by side in each layer with the strips in one layer staggered with relation to the strips in an 60 adjacent layer and a fabric retainer having a plurality of superposed pockets formed therein, said fabric and pockets retaining the strips in each layer side by side and the superposed strips in staggered position with 65 relation to the strips in an adjacent layer.

5. A flexible protective armor consisting 70 of a plurality of superposed layers of elongated comparatively narrow thin flexible steel strips, said strips being laid side by side in each layer with the strips in one layer 75 staggered with relation to the strips in an adjacent layer and a fabric retainer having a plurality of superposed pockets formed therein, said fabric and pockets retaining the strips in each layer side by side and the superposed strips in staggered position with 80 relation to the strips in an adjacent layer, said fabric adapted to be impregnated with an adhesive to secure the strips against removal from the pockets.

ARTHUR E. TROIEL.
